UNITED STATES PATENT OFFICE.

LEWIS J. MURRAY, OF BIRMINGHAM, COUNTY OF WARWICK, ENGLAND.

DESIGN FOR A FLOWER-STAND.

SPECIFICATION forming part of Design No. 18,702, dated October 23, 1888.

Application filed September 22, 1888. Serial No. 286,126. Term of patent 3½ years.

To all whom it may concern:

Be it known that I, LEWIS J. MURRAY, of Birmingham, England, have originated and produced a new and original Design for a 5 Flower Stand or Holder, of which the following is a specification.

My design consists in making an upright tube in the form of a trunk of a plant, in providing the base thereof with representation of 10 leaves or the like, and in providing the upper end with a flange-like projection made in the form of leaves of a plant.

The accompanying drawing is a perspective view of a flower stand or holder embodying 15 my design.

A designates an upwardly-extending tube or receptacle. It is made to represent the trunk of a plant. At the base the stand or holder is embellished with representations, B, of leaves

or like devices. At the upper end there is a 20 flange-like projection, C, made to represent leaves of a plant.

The design as illustrated is specially adapted to represent a palm-tree.

What I claim as new, and desire to secure by 25 Letters Patent, is—

A design for a flower stand or holder, consisting of a tube made in the form of a trunk of a plant, a base made to represent leaves or like devices, and an outwardly-extending 30 flange at the upper end, made to represent leaves of a plant, substantially as shown and described.

LEWIS J. MURRAY.
